FRED F. FIELD, JR., OF BROCKTON, MASSACHUSETTS, ASSIGNOR TO FIELD & FLINT CO.,
OF BROCKTON, MASSACHUSETTS, A CORPORATION OF MASSACHUSETTS

SHOE CALK

Application filed April 12, 1929. Serial No. 354,626.

My invention, which relates to shoe calks, and has among its objects the provision of a calk which, among other things, will be supported in an improved manner, and will prevent the adherence of cakes of mud thereto, will be best understood from the following description when read in the light of the accompanying drawing of an embodiment thereof submitted for illustrative purposes, while the scope of the invention will be more particularly pointed out in the appended claim.

In the drawing:—

Fig. 1 is an elevation of the shoe calk constructed according to the invention;

Fig. 2 is a plan according to Fig. 1;

Fig. 3 illustrates one manner of securing the calk to a sole leather, and is a section on the line 3—3 of Fig. 4, the latter being a plan according to Fig. 3.

Referring to the drawing, the shoe calk illustrated comprises a frusto-conical body portion 1, the latter having a flat circular base 3 of relatively large diameter and, opposite this base, a relatively steep frusto-conical side 5. Coaxially formed with the body portion at the apex thereof is a spike 7 having a relatively quick tapered frusto-conical surface 9, the construction being such as to provide a much smaller angle α between the surfaces 5 and 9 than heretofore employed in shoe calks.

I have found that by making the under side of the body portion rather steep, say by giving it a taper of about $4\frac{1}{2}$ to 1, and making the spike of a relatively quick taper, say about 1 to 2, with the result that the angle α is approximately $1\frac{1}{2}$ quadrants of a circle, the possibility of mud clinging to the spike is practically eliminated, especially when the body portion is of relatively large diameter, say from about $\frac{7}{16}$ to $\frac{9}{16}$ of an inch, a diameter of approximately $\frac{1}{2}$ inch under these conditions giving excellent results.

As illustrated, the body portion of the calk

is integrally formed with an axially positioned tubular rivet 11, the length of the rivet and the thickness of its walls being such that when the rivet is secured to a sole leather of normal thickness, say one from about $\frac{1}{16}$ to $\frac{1}{4}$ of an inch thick, the flange 13 formed by the riveting operation will have a diameter of about that of the body portion, this result preferably being secured by use of a rivet set so shaped as to flare outwardly the walls of the shank of the rivet, as indicated at 15, this flare also minimizing radially splitting the flange, because the flange is not bent at as acute an angle as it would be were the walls of the shank not flared as with prior constructions where the splits 17 (Fig. 4) in the flange 13 are wide and extend radially inward to the body of the shank.

I have found that with shoe calks heretofore constructed there is a tendency for the calk to cant with great discomfort to the wearer, especially if the calk becomes loosened. The outward flaring of the walls of the tubular rivet according to the present invention tends to expand the thickness of the leather between the flange 13 and body portion 5, causing the calk firmly to grip the leather and prevent loosening of the calk, while the outwardly and upwardly flaring side of the shank coacts with the large diameter surface 3 to resist canting of the calk.

It will be understood that the invention is not limited to the details of the specific embodiment thereof herein described, and that within the scope of the invention wide deviations from these may be made without departing from the spirit of the invention.

Claim:

A sole leather having a calk provided with a body portion abutting one side of said leather, a spike carried by said body portion, a tubular part integral with said body portion extending through said leather, a comparatively narrow flange carried by said tubular part abutting the opposite side of

said leather, the exterior diameter of which flange is relatively large, said tubular part having relatively quickly, outwardly and upwardly flaring walls integral with said flange, whereby said leather may be expanded in thickness between said flange and body portion to prevent loosening of said calk and said flange and tubular part may be formed without splitting of said tubular part or material splitting of said flange.

10 In testimony whereof, I have signed my name to this specification.

FRED F. FIELD, JR.
